Brock & Smith

Atty's

UNITED STATES PATENT OFFICE.

ANDREW J. SANFORD, OF NEWARK, OHIO, ASSIGNOR TO A. H. HEISEY & CO., OF
NEWARK, OHIO.

DESIGN FOR A GLASS ARTICLE.

60,706.

Specification for Design. Patented Mar. 21, 1922.

Application filed July 7, 1919. Serial No. 309,240. Term of patent 3½ years.

To all whom it may concern:

Be it known that I, ANDREW J. SANFORD, a citizen of the United States, residing at Newark, Ohio, have invented a new, original, and ornamental Design for a Glass Article, of which the following is a specification, reference being had to the accompanying drawing, forming part thereof.

The drawing is a side elevation of a molasses can embodying the invention.

I claim—

The ornamental design for a glass article, substantially as shown.

ANDREW J. SANFORD.
